SASH OPERATOR

Myron S. Kennedy, Sr., Goshen, and Eldon L. Krieg,
South Whitley, Ind.

Application August 22, 1952, Serial No. 305,792

2 Claims. (Cl. 74—424.8)

Our invention relates broadly to building construction and more particularly to a sash operator for opening and closing pivoted sash.

One of the objects of our invention is to provide a construction of sash operator which may be readily applied to pivoted sash as it is fabricated and readily installed with the sash for moving the sash into open or closed position.

Another object of our invention is to provide a construction of sash operator which may be readily applied to hinged sash already installed and utilized to conveniently open or close the hinged sash.

A further object of our invention is to provide a construction of pivoted window sash and a crank operated device associated therewith and connected to an arm pivotally connected with the sash for opening and closing the sash from an interior position adjacent the casement of the window.

Still another object of our invention is to provide a novel construction of sash operator hardware including a housing, an angularly shiftable screw operated by a rotatable crank and a connecting rod engaging the screw and pivotally connected with the swinging arm of a hinged window sash for conveniently opening or closing the window with respect to the casement.

Other and further objects of our invention reside in the association of a screw actuated operator and the swinging arm of a pivoted window sash whereby control of the window sash may be effected from a remote position, as set forth more fully in the specification hereinafter following by reference to the accompanying drawings, in which:

Figure 1 is a vertical sectional view through the casement of a window and illustrating a horizontally pivoted window sash controlled by the sash operator of our invention, the view showing the window sash in closed position with respect to the window casement; Fig. 2 is a view similar to the view illustrated in Fig. 1 but showing the sash operator in actuated position for opening the window with respect to the casement; Fig. 3 is a fragmentary elevational view of the casement and window shown in Figs. 1 and 2; Fig. 4 is a fragmentary perspective view of the sash operator of our invention and the connection thereof with the arm of the pivoted sash and showing the housing of the sash operator in longitudinal section; Fig. 5 is a transverse sectional view through the sash operator of our invention; Fig. 6 is a fragmentary horizontal sectional view taken substantially on line 6—6 of Fig. 2; Fig. 7 is a fragmentary horizontal sectional view taken substantially on line 7—7 of Fig. 2; Fig. 8 is a fragmentary horizontal sectional view through a casement, window sash and the associated screen assembly of the type in which the sash is vertically pivoted in the casement for horizontal swinging movement of the sash with respect to the casement, the view showing the window in closed position; Fig. 9 is a view similar to the view shown in Fig. 8 illustrating the window sash moved to open position; Fig. 10 is a fragmentary ele-

2

vational view of the window screen and casement as shown in Figs. 8 and 9 and illustrating the sash operator of our invention in vertical section extending through a mortise formed in the frame of the screen; Fig. 11 is a detailed view in fragmentary vertical section illustrating the manner in which the sash shown in Figs. 8 and 9 is guided with respect to the sill plate of the casement; Fig. 12 is a vertical sectional view taken through the sash operator of our invention as applied to swinging windows of the type illustrated in Figs. 8 and 9; Fig. 13 is a horizontal sectional view through the sash operator shown in Fig. 12; Fig. 14 is a vertical sectional view taken on line 14—14 of Fig. 12; Fig. 15 is a detailed plan view of the connection means between the sash arm and the sash operator; and Fig. 16 is a cross sectional view on line 16—16 of Fig. 15.

Our invention is directed to a construction of sash operator for casement windows having swinging window sash. The sash operator of our invention may be fabricated with and form a part of the swinging window sash as it is delivered for installation, or the hardware of our invention may be very readily applied to swinging window sash already in use by simply drilling a single hole in the conventional arm of the swinging window sash and attaching the hardware of our invention to the casement in a position in which the operating crank of the sash operator is conveniently accessible interiorly of the window casement and which may be rotated for opening or closing the window. Our invention is equally adaptable to swinging window sash pivoted for horizontal swinging movement or swinging movement in a vertical plane.

The sash operator of our invention is equally adaptable for both metal and wood window casements and frames. In showing the hardware of our invention applied to a wood casement and wood frame, we desire that it be understood that a similar application thereof may be made to metal casements and metal sash.

The hardware of our invention comprises an elongated housing attachable to the window casement in which a longitudinally extended screw is disposed and which is angularly shiftable in position within the housing by an orientatable connection thereof through the end wall of the housing and wherein a crank is secured to an extension of the screw which projects through the end wall of the housing. The rotatable screw engages a screw threaded follower intricately formed with an arm which forms a pivotal connection with the conventional arm of the swinging window sash whereby operation of the crank serves to open or close the sash with respect to the casement. The housing for the sash operator may be conveniently passed through a mortise in the edge of the frame of the window screen, enabling the crank to be operated from the interior of the casement and the window to be moved to closed or open position exteriorly of the sash.

We have found the hardware of our invention very practical and efficient in operation, but we realize that modifications may be made, and we desire that the construction set forth herein be considered in the illustrative sense rather than in the limiting sense.

Referring to the drawings in more detail, reference character 1 designates the casement of the window including the casement jamb 2 and the casement plates 3 at opposite sides of the casement. The casement plates 3 include vertically extending trackways 4 shown more clearly in Figs. 4 and 7 and within which the sliding shoes 5 are vertically adjustable in position. In order to eliminate lost motion and provide for the smooth running of the sliding shoes 5, suitable friction springs are employed which yieldably maintain the connection between the sliding shoes 5 and the trackways 4. The sliding shoes 5 form

pivotal connections at 6b for the sash plates 6 which project outwardly therefrom. The sash plates 6 are apertured at spaced intervals shown at 6a for the attachment of sash 7 thereto, enabling the sash to swing with respect to the casement under control of the sliding shoes 5 to which the sash plates 6 are pivoted at 6b. The casement plates 3 also provide pivotal connections 8 for the arms 9 which are pivotally connected at the ends thereof at 6c with the sash plates 6. The arms 9 are fixedly pivoted at 8 with respect to the casement plates 3 while the sliding shoes 5 are adjustable in the trackways 4 of casement plates 3. One of the arms 9 is apertured at 9a intermediate the distance between the fixed pivot 8 and the orientatable pivot 6c. The hardware of our invention is pivotally attached to the arm 9 at the aperture 9a therein by means of the screw connection 10 carried by the extension arm 11 to which the follower screw 12 is integrally attached.

The screw connection 10 is provided with a shoulder to insure an angularly movable precision joint between arm 9 and extension arm 11 that is substantially permanent in character and cannot normally be tampered with. This is accomplished by providing a recess 10a in the head of screw 10 that is engageable only by a special wrench which will fit the recessed socket for assembling the arms or for disassembling the arms for purposes of repair and maintenance.

The follower screw 12 projects from one side of the extension arm 11 into the path of the operating screw 14 which engages the follower screw 12 at one end and which is provided with a smooth cylindrical shank 15 at its other end. The operating screw 14 is provided with a circular flange 16 intermediate the screw threaded portion and the smooth cylindrical shank 15. The circular flange 16 serves as an abutment fulcrum for the inner end wall 17 of the housing 18 which is apertured at 19 for the passage of the smooth cylindrical shank 15. The aperture 19 in the end wall 17 of the housing is shaped in the form of two truncated cones directed toward each other and terminating in annular edged portion 19a intermediate the inner and outer faces of the end wall 17 to provide substantially a line bearing which supports the smooth cylindrical shank 15 in a position in which the screw 14 may shift angularly from a central position to a position directed toward one of the side walls 20 of the housing 18. The housing 18 is approximately U-shaped in section, closed on three sides and open on the side which is engaged against the casement 1. The side of the housing 18 which engages the casement 1 is provided with longitudinally extending flanges 18a and 18a' through which screws 21 pass for securing the housing to the casement 1. The end of the smooth cylindrical shank 15 which projects through the end of the housing 18 is provided with the rotatable crank 22 which may be revolved from a position interiorly of the casement 1 for rotating screw 14 and driving follower screw 12. To allow for the angular shifting of the extension arm 11 and follower screw 12, the housing 18 is constructed in two different transverse widths represented at 18b and 18c. The width 18b comfortably accommodates the follower screw 12 which progressively moves therein to a position abutting the circular flange 16 when the sash is fully closed with respect to the casement jamb 2 as illustrated in Fig. 1. When, however, the crank 22 is revolved for rotating screw 14, the follower screw 12 is advanced to a position in which it is released from the parallel extending walls of the section 18b of the housing 18 to an intermediate position where the walls of the housing diverge through the zone represented at 18d, permitting the screw 12 to be angularly displaced and thereafter provided with ample space within which to angularly shift by reason of the broadened special relation between the side walls of the housing in the area designated at 18c. It will be observed that the inside walls of housing 18, both in the area 18b and in the area 18c, are linear and parallel, interconnected by the diverging walls 18d. This facilitates the angular displacement of the fol-

lower screw 12 from the central position to the displaced position which it occupies when the window sash is moved to the open position illustrated in Fig. 2.

When the hardware of our invention is applied to window sash of the vertically pivoted type, the operation is substantially the same as is represented in Figs. 8-14. In this arrangement the window sash is represented at 23 operating within casement 1, the window casement being provided with a sill plate 24 having a horizontal trackway 25 therein in which sliding shoe 26 moves horizontally from right to left and vice versa. The sill plate 24 is provided with a pivot 27 therein to which there is attached one end of the arm 28, the other end of which is pivotally connected at 31 to the sash plate 29. Sash plate 29 is pivotally connected at its remote end to the sliding shoe 26 as indicated at 30. The sash plates 29 at the top and bottom of the sash 23 serve to support sash 23 in a position in which the sash may be moved with respect to the side of the casement 1 in opening or closing the window. The sash operator is constructed as explained in connection with Figs. 1-7 wherein the housing 18 is attached by screws 21 to the horizontally extending casement 1. The extension arm 11 of follower screw 12 connects to the pivot 32 in arm 28 intermediate the pivotal connection 27 and the pivotal connection 31.

The screen shown at 33 is readily mortised at the lower edge thereof as represented at 34 for the passage of the housing 18 as represented in Fig. 10. The operating screw 14 and the follower screw 12 angularly shift about in annular fulcrum edge 19a of aperture 19 in end wall 17 of housing 18 as the angular position of the sash is shifted as represented in Figs. 9 and 13. As heretofore explained, the difference in transverse section of the parts 18b and 18c of housing 18 enable the follower screw 12 and arm 11 to move through a relatively large angle as the follower screw 12 is advanced outwardly from the housing. We arrived at this construction after computing the relatively small angular displacement of arm 11 throughout one portion of the angular path of travel of sash 23 as compared to the larger angular displacement of follower screw 12 and associated arm 11 for the remainder of the angular path of travel of the window sash.

We have found the sash operator of our invention highly practical in its construction, and while we have illustrated preferred forms of our invention, we realize that modifications may be made, and we desire that it be understood that no limitations upon our invention are intended other than may be imposed by the scope of the appended claims.

What we claim as new and desire to secure by Letters Patent of the United States is as follows:

1. An operator for swinging sashes comprising a protective housing formed by a cover terminating in attachment flanges coextensive with approximately one-half the linear axis of said housing and disposed adjacent an open end of said housing, a wall closing the other end of said housing remote from the aforesaid open end, said wall being centrally apertured, a rotatable operating member disposed in said housing and having a smooth cylindrical shank extending through said apertured wall and a screw-threaded shank disposed within said housing, a circular flange on said rotatable operating member intermediate said smooth cylindrical shank and said screw-threaded shank and operating as a pivot means with respect to said apertured end wall for orientation of said rotatable operating member with reference to the interior of said housing and a screw follower engaging and operated by said screw-threaded shank and orientable in consonance with the orientation of said rotatable operating member and wherein in said protective housing has a transverse section adjacent the closing wall of the housing which is sufficient to guide the translatory movement of said screw follower and wherein the transverse section of said housing adjacent the other end thereof has its side walls more widely spaced to permit the relatively wide transverse displacement of

said screw follower as the circular flange on said operating member is displaced about said apertured end wall as a pivot.

2. An operator for swinging sashes comprising a protective housing formed by a cover terminating in attachment flange coextensive with approximately one-half the linear axis of said housing and disposed adjacent an open end of said housing, a wall closing the other end of said housing remote from the aforesaid open end, said wall being centrally apertured, a rotatable operating member disposed in said housing and having a smooth cylindrical shank extending through said apertured wall and a screw-threaded shank disposed within said housing, a circular flange on said rotatable operating member intermediate said smooth cylindrical shank and said screw-threaded shank and operating as a pivot means with respect to said apertured end wall for orientation of said rotatable operating member with reference to the interior of said housing and a screw follower engaging and operated by said screw-threaded shank and orientatable in consonance with the orientation of said rotatable operating member

and in which said attachment flanges connect with side walls of said housing which are relatively widely spaced throughout approximately one-half the linear axis of said housing and wherein the opposite end portion of said housing is provided with side walls which are more narrowly spaced than the aforesaid side walls, and tapered walls interconnecting the first mentioned more widely spaced side walls and said second mentioned more narrowly spaced side walls.
